(57) **CLAIM**

The ornamental design for telescopic net, substantially as shown and described.

DESCRIPTION

FIG. 1 is a folded perspective view of its front, showing my new design;

FIG. 2 is an open perspective view of its front;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is its disassembled plan view; and,

FIG. 10 is an enlarged detail view of area 10 in FIG. 1. The broken lines in the drawings illustrate the portions of telescopic net, which form no part of the claimed design.
